UNITED STATES PATENT OFFICE.

LEWIS CUATT, OF UNION CITY, MICHIGAN.

EXPANDING MOLD.

SPECIFICATION forming part of Letters Patent No. 770,677, dated September 20, 1904.

Application filed January 27, 1904. Serial No. 190,855. (No model.)

To all whom it may concern:

Be it known that I, LEWIS CUATT, a citizen of the United States, and a resident of Union City, Branch county, State of Michigan, have 5 invented certain new and useful Improvements in Expanding Molds; and my preferred manner of carrying out the invention is set forth in the following full, clear, and exact description, terminating with claims particularly 10 specifying the novelty.

This invention relates to apparatus for forming plastic blocks, more especially to that class called "expanding molds;" and the objects of the same are to construct a mold of this character whose parts shall be interchangeable and to provide improved means for raising the bottom.

To this end the invention consists in the details described below and illustrated in the 20 drawings, wherein—

Figure 1 is a perspective view of this mold. Fig. 2 is a perspective view with one side and both ends partially open and the other side removed. Fig. 3 is a section on line xx , Fig. 2. 25 The bed of this machine comprises a rectangular frame 1, from whose corners project right-angular brackets 2, all these parts being rigid and suitably supported. The sides 3 and ends 4 (herein called "members") are 30 supported on the bed in like manner, and a description of one will suffice for all.

5 represents bearing-blocks slotted at 6 for the reception of bolts 7, which pass through the brackets 2 to permit the blocks to be adjusted from or toward the center. There is a pair of such blocks for each member and in them are journaled stub-shafts 8, projecting from the extremities of a rock-bar 9, which when upright stands about flush with the upper face of the bottom board. The member supported by this rock-bar has strips 10, slotted as at 11, whereby it is vertically adjustable by means of bolts 12, which pass through the rock-bar. Two of the members, as the 45 ends 4, have hooks 20 projecting beyond their upper corners, and the other two members have latches 21, which engage the hooks when all the members stand vertical. It will be clear that when a larger mold is required the end 50 members (if the product is to be longer) must

be set farther from the center by adjusting the bearing-blocks of one or both of them, and when so set the side members must be replaced by others which are of proper length. All interchangeable members will have their 55 straps 10 spaced the same distance from each other, so as to properly engage the bolts 12, and hence different members within the limits of the size of the machine can be supported on the same rock-bars. So, also, with members of different height. 60

The bottom 40 is here shown as a flat board, and one of different size will replace the one illustrated when a product of different size is to be produced. I have discovered that this 65 bottom board often warps, shrinks, and swells, and it is therefore desirable that firm and positive means be employed for raising it bodily upward and pressing it closely against the edges of all the members. For this purpose I employ a pair of levers 30, each pivoted at 31 in one side of the bed with its handle projecting beyond the other side, and to this lever is pivoted at 32 a T-shaped cam 33, whose outer and wider end has projections 34 70 resting upon beveled notches 35, cut in the ends of the bed. Whenever the lever is moved in the proper direction, its cam is forced outward, and the projections, riding up the beveled notches, cause the head of the cam to rise. 75 When both cams are thus elevated, the bottom 40 is raised firmly by their heads, which extend entirely across beneath each end of the bottom board. 80

I have not illustrated a plunger for the 85 reason that this mold is capable of producing a product which is allowed to set, or it could be employed in producing a product which is made under pressure, all without departing from the spirit of my invention. 90

The parts are of proper sizes, shapes, proportions, and materials, and additions or slight alterations may be made as necessity requires.

What is claimed as new is—

1. In a mold, the combination with the bed 95 having right-angular brackets at its corners, a bottom, and interchangeable upright members; of a pair of bearing-blocks secured to each pair of parallel brackets with means for radial adjustment, a rock-bar pivoted between 100

said blocks, and upright straps on the various members correspondingly spaced from each other and detachably connected with said rock-bar.

5. 2. In a mold, the combination with the bed having right-angular brackets at its corners, a bottom, and interchangeable upright members; of a pair of bearing-blocks secured to each pair of parallel brackets with means for 10 radial adjustment, a rock-bar pivoted between said blocks, upright straps on the various members correspondingly spaced from each other and provided with slots, and bolts passing through the rock-bars and engaging said 15 slots to permit vertical adjustment of the members.

3. In a mold, the combination with the bed, the upright members, and the bottom; of means for raising the bottom consisting of 20 two T-shaped cams with their heads remote from each other, projections on said heads,

inclined supports on which the projections rest, and mechanism for moving the cams away from each other.

4. In a mold, the combination with the bed, 25 the upright members, and the bottom; of means for raising the bottom consisting of two T-shaped cams with their heads remote from each other, projections on said heads, beveled notches in the ends of the bed on 30 which the projections rest, and levers pivoted to the shanks of the cams and fulcrumed in the bed with their handle ends projecting from the same.

In testimony whereof I have hereunto subscribed my signature this the 22d day of January, A. D. 1904.

LEWIS CUATT.
